GRASS SHEAR

Thomas J. Caves, 6952 Town Lane,
Dearborn Heights, Mich. 48127

Filed Mar. 5, 1969, Ser. No. 16,071

Term of patent 14 years

Int. Cl. D8—01

U.S. Cl. D8—8

FIG. 1 is a perspective view of a grass shear shown broken away for convenience of illustration.

FIG. 2 is a partial front elevational view; and

FIG. 3 is a detail side elevational view of the lower portion of the shear.

The broken lines showing the electric drill in FIGS. 1 and 2 are for illustrative purposes only.

I claim:

The ornamental design for a grass shear, as shown and described.
